WIRE DISPENSING MEANS

Filed Feb. 18, 1930

UNITED STATES PATENT OFFICE

HENRY AUGUSTUS VESEY, OF FORT SMITH, ARKANSAS

WIRE DISPENSING MEANS

Application filed February 18, 1930. Serial No. 429,294.

This invention relates to the means for dispensing wire from relatively large coils thereof and is primarily intended to provide a means whereby wire may be paid out from large coils without any possibility of becoming kinked or otherwise tangled by reason of expanding action as the wire is withdrawn from the coil. In dispensing wire from large reels it is quite often the case that knots, 5 kinks, and serious tangles result when the wire is extended over any considerable distance, this being due to the spiral action which is encountered when wire is paid out from a coil. The present invention has been 10 designed to overcome these defects and objectionable characteristics of coil wire.

Objects of the invention are: to provide a means for dispensing wire from large coils without kinking and tangling thereof; to provide a reel for coil wire having a dispensing guide whereby kinking of the wire is prevented; to provide a novel coil supporting 20 means equipped with guide means whereby the coil may be paid out in any direction with perfect freedom from kinking; to provide a reel holder in the form of a container having self-contained guide means for dispensing a coil mounted within said container; and generally to provide improved 25 and novel means for dispensing relatively large coils without danger of tangles and kinks resulting therefrom.

The accompanying drawings illustrate a practical embodiment of the principles of 30 this invention but the disclosure does not constitute a limitation upon the scope thereof. In the drawings:

Figure 1 is a section, partly in elevation, 35 through a container having a coil of wire supported therein and in position for dispensing through the guide means with which the container is equipped.

Figure 2 is a horizontal section on the line 2-2 of Figure 1.

Figure 3 is a vertical section enlarged on the line 3-3 of Figure 1.

In the form as shown the invention comprises a container in the form of a casing 10 of squared form suitable for housing a relatively large coil of wire and which is pro-

vided with a handle 11, one side of the casing comprising a hinged cover 12 which is adapted to be secured in closed position by a suitable fastener 13. Opposite the hinged wall 12, the container wall 14 has secured thereto a substantially frusto-conical core piece 15 which projects laterally across the entire interior of the container and extends through and beyond the hinged wall 12 when the same is in closed position as fully shown 55 in Figure 1.

The wall 12 is apertured to receive the adjacent end of the core 15 therethrough and, in the form as illustrated, the projecting end of the core is covered by a funnel-shaped hood 16 having its flared lower end rigidly secured to the body of the wall 12 by suitable fastening elements 17; a rim flange 18 on the end of the hood cooperating with the wall 12 to clamp therebetween an annular gasket 19 60 of some suitable elastic material, which gasket 19 is formed with an aperture 20, the edge of which bears with some force downwardly against the inclined adjacent surface of the frusto-conical guide 15. The body of the gasket 19 fills the space intervening between the wall 12 and the core.

The restricted neck 21 of the hood 16 is formed for connection with a flexible tubing 22 of any desired length, which cooperates 65 with the hood 16 to form a guide through which the wire 23 is paid out from a coil 24 positioned over the core 15 in the container.

In service, the hinged cover 12 is opened and the coil 24 seated over the core 15, a free end of the wire being passed through the friction guide aperture 20 and through the tube 22, after which the cover 12 is closed and secured by the catch 13. In this closing 70 of the cover the friction guide means which in the illustrated embodiment is the gasket 19, is caused to bear against the face of the core 15, binding the wire 23 thereagainst with sufficient force to restrain the same against coiling as it is drawn out through the flexible 75 guide 22.

The presence of the friction guide 19 imparts a tension on the wire in the hood 16, thereby maintaining it as an open coil, eliminating any possibility of kinking.

It is within the province of this invention that either or all of the tube 22, hood 16 and gasket 19 may be dispensed with if desired, and the body of the cover 12 may be made to replace the gasket. Also, the core 15 may be so disposed as to project through the cover 12 or lie just beneath the same. The container may be of open frame construction and may be formed as a cardboard carton serving as a shipping unit if desired.

An important feature of my invention resides in its application to use as a means for coating wire with soapstone, which coating is a requirement prior to drawing wire through metal conduits. The soapstone may be placed in the container with the coil so that the wire will be coated within the container.

While in this embodiment of the invention I have illustrated and described certain structural details and materials, it is to be understood that any desired changes and modifications may be made in such details as will fall within the scope of the invention as claimed.

I claim:

1. Coil dispensing means comprising a substantially rectangular container, a core secured therein and extending transversely thereacross, one wall of said casing being apertured in registry with said core, and substantially flexible means carried by said wall and cooperating with said core to impart frictional restraint to the material paid out from a coil when mounted on said core in the container.

2. Coil dispensing means comprising a substantially rectangular container, a hinged closure therefor, a core in said container, said closure having an opening in registry with said core, means on said closure adjacent said opening for cooperating with said core to impose frictional restraint on the material passed from said container through said opening, and a guide carried by said closure in registry with said opening therein.

3. Coil dispensing means comprising a substantially rectangular, container, a hinged closure therefor, said closure having an opening formed therein, a core in said container and extending transversely thereacross to project through said closure opening, a flexible guard carried by said closure and surrounding the projecting portion of said core, and a guide carried by said closure above the opening provided therein.

4. Coil dispensing means comprising a substantially rectangular container having one wall thereof provided with an opening, a core in said container having one end thereof in registry with said opening, a coil on said core with a free end extending through said opening, and means on said container for yieldingly pressing the coil against said core as it is drawn through said opening.

5. Coil dispensing means comprising a sup-

port, a coil mounting member carried thereby, said support and member having complementary cooperating means imposing constant frictional restraint on material paid out from a coil on the mounting member.

6. Coil dispensing means comprising a container having a wall provided with an opening, a coil holding core in said container and in registry with said opening, and said wall having a resilient portion adjacent its opening for yieldingly pressing against the core material passed through said opening from the core.

7. Coil dispensing means comprising a container having a wall provided with an opening, a coil holding core in said container and having a substantially rounded portion disposed in the opening, and a resilient gasket on said wall and bearing against the substantially rounded portion of the core, said gasket being centrally apertured for the passage therethrough of material paid out from the core.

In testimony whereof I affix my signature.

HENRY AUGUSTUS VESEY.
